UNITED STATES PATENT OFFICE.

WILLIAM H. MILLER, OF CLEVELAND, OHIO.

FAUCET.

1,186,116.

Specification of Letters Patent.

Patented June 6, 1916.

Application filed March 1, 1915. Serial No. 11,265.

To all whom it may concern:

Be it known that I, WILLIAM H. MILLER, a citizen of the United States, residing at Cleveland, in the county of Cuyahoga and State of Ohio, have invented certain new and useful Improvements in Faucets, of which the following is a specification.

This invention relates to improvements in faucets, and the improvements comprise the simple organization of parts substantially as herein shown and described and more particularly pointed out in the claims.

The object of the invention resides in the double-acting stem for the faucet and in the valve and its adjustable extension whereby the discharge of liquid may be regulated to correspond to different pressures, and further objects are embodied in the packing washer for the valve stem, and in the simple screw regulator for the spout end of the faucet, as well as in the mode of fastening the handle to the stem.

In the accompanying drawings, Figure 1 is a sectional view vertically and longitudinally of the faucet, and Fig. 2 is a plan section on line 2—2, Fig. 1. Fig. 3 is a cross section on line 3—3, of Fig. 4 showing the screw regulator for the outlet end of the faucet, and Fig. 4 is a vertical section of the same device. Fig. 5 is a side elevation of the handle and valve operating stem. Figs. 6 and 7 are side and end views of the valve and its fluted extension.

The faucet comprises a body 2 having a main water passage 3 of uniform bore intersected by a round chamber 4 of larger diameter which extends upwardly through a screw-threaded neck 5 midway between the ends of said body. Said neck 5 is surmounted by a cap nut 6 in sleeved engagement with the reduced upper end 7 of the valve operating member which has its main portion 8 relatively enlarged and of smooth cylindrical form to fit snugly within the upper end of chamber 4, and the lower end or straight oval extension 9 of said member rests in rotatable engagement with the flat bottom 10 of said chamber. A beveled metal washer 11 bears against the flat shoulder 12 at the upper end of the enlarged portion 8 of the rotatable valve operating member or stem, and said washer also rests upon the top flat surface of neck 5. The beveled edge 14 of the washer is placed uppermost to compress the packing material 15 within the recessed cap nut 6 and thereby expand it inwardly

against the stem and also outwardly and downwardly adjacent the beveled edge of the washer to seal the screw-joint between the nut and the neck. To do this, the washer is relatively smaller in diameter than the recess holding the packing material in the nut and also slightly smaller in diameter than the flat end of the neck. The washer, packing and cap nut are sleeved upon the reduced stem 7 before the handle 15 is secured thereto; and a simple, cheap and practical mode of fastening the handle upon the stem is by compressing and contracting the round-middle head 16 of said handle in a vise or other pressure-applying device.

The lower oval extension 9 of the handle member projects across the main water passage 3 and a quarter turn of the handle in either direction will open the valve 17 as is obvious when it is noted that said extension projects on both sides of its axial center equal distances and that the oval cross sectional formation of this extension provides a double cam adapted to engage with the flat extremity 18 of the adjustable contact member 19 for valve 17. Member 19 has a screw-threaded stem 20 to enter one end of the screw-threaded central bore of the fluted guide 21 of the valve, and the said valve is of metal and flaring and has a short screw-threaded nipple 21 of its own to secure it tightly against the outer end of the guide 21. Member 19 is also fluted longitudinally for the free passage of water, and the valve 17 is slidably held in true and fixed alignment with the central opening in the valve seat 23, which is a removable ring of Babbitt metal, preferably. A conical projection 24 on the outer flat face of valve 17 centers the smaller end of a spiral spring 24', and the larger end of said spring is seated at the base of a valve chamber produced in the tubular shank 25 which is detachably screwed upon the screw-threaded end 26 of body 2. Shank 25 is provided also with a reduced screw-threaded nipple 27 adapted to screw into a pipe fitting or other service pipe connection, and a backing flange 28 is removably seated at the rear of the shank.

Spring 24' and the pressure of the water hold valve 17 tightly upon its seat and the movement forward is limited by the seat, but the movement rearward may be increased or decreased to open the valve more or less to suit different water pressures. In

2

this way also the flow of water at the outlet of the faucet may be modified to meet different requirements and the desired degree of movement of valve 17 is determined and obtained by adjusting the fluted contact member 19 longitudinally within the bore of the fluted guide so as to project the flat end of said member more or less into chamber 4 in the rotary path of the double cam extension 9. Wear on the valve seat may also be accommodated by adjustment of member 19.

The faucet shown is also provided with a detachable drinking spout 30 constructed to restrict and regulate the flow of water for fountain effects. Thus, the end of the spout has a flaring seat 31 covered by a screw-cap and hollow head 32, and a removable screw plug 33 is adjustably fixed within the spout end to control the outflow, which is in a thin sheet or film as regulated by the round flaring head 34 extending upwardly and outwardly from the reduced neck 35. The body of the screw plug has a central slot 36 extending from the bottom to the annular space or channel surrounding neck 35, thus providing a water way and also two spring body sections which act to lock the screw plug in any adjusted position. The flat upper end of the flaring head 34 has a screw driver kerf which may be

reached through the central discharge openings in screw cap 32 when adjustment is desired.

What I claim is:

1. A faucet body having a valve and a seat therefor, and provided with a tubular neck and a shouldered valve stem seated therein, in combination with a flat washer seated upon said shouldered stem and upon the top of said neck and provided with a beveled edge, and a cap nut in screw engagement with said neck having a compressible packing above said washer and surrounding its beveled edge. 45

2. A faucet body for fountain purposes having a water passage provided with a valve seat at its end, a valve for said seat and a fluted stem carrying said valve consisting of two members adjustably connected and adapted to be lengthened and shortened according to the water pressure, and a rotatable handle having an elliptical end portion adapted to engage said valve stem and open the valve more or less according to the length of said valve stem. 50

In testimony whereof I affix my signature in presence of two witnesses.

WILLIAM H. MILLER.
